UNITED STATES PATENT OFFICE.

MICAJAH L. POULTER, OF MOUNT PLEASANT, IOWA.

DITCHING-MACHINE.

1,186,036.

Specification of Letters Patent.

Patented June 6, 1916.

Application filed May 10, 1915. Serial No. 27,159.

To all whom it may concern:

Be it known that I, MICAJAH L. POULTER, a citizen of the United States, residing at Mount Pleasant, in the county of Henry 5 and State of Iowa, have invented certain new and useful Improvements in Ditching-Machines; and I do declare the following to be a full, clear, and exact description of the invention, such as will enable others 10 skilled in the art to which it appertains to make and use the same.

My invention relates broadly to improvements in excavating machines and more particularly to those primarily designed for 15 ditching purposes.

The object of the invention is to improve upon the general construction of devices of this class to such an extent as to provide a very simple machine, yet one which will be 20 highly efficient in operation and will possess a number of advantageous features.

With this general object in view, the invention resides in certain novel features of construction and combination hereinafter 25 fully described and particularly pointed out in the appended claims.

In describing the invention, I shall refer to the accompanying drawings wherein like reference characters designate corresponding 30 parts throughout the several views and wherein:—

Figure 1 is a sectional view of an excavator constructed in accordance with my invention, this view being taken substantially 35 on the plane indicated by the line 1—1 of Fig. 2; Fig. 2 is substantially a front view of the excavator; Fig. 3 is an elevation of the framework with parts broken away and in section; Fig. 4 is an enlarged detail side 40 elevation of a portion of one of the chains; Fig. 5 is an outer side view of the parts seen in Fig. 4; Fig. 6 is a longitudinal section as seen along the plane indicated by the line 6—6 of Fig. 5; Fig. 7 is a front elevation of 45 a portion of the excavator showing the application thereto of a plurality of stiffening bars to be described; Fig. 8 is a horizontal section as seen along the plane indicated by the line 8—8 of Fig. 7; Figs. 9 and 10 are 50 respectively side and plan views of a slightly modified form of excavating and elevating member; and Figs. 11 and 12 are views similar to Figs. 9 and 10 respectively, showing yet another type of excavating and 55 elevating member.

In these drawings, constituting a part of the application, I have shown only the parts

of the complete machine wherein reside the numerous novel features of the invention, all of these parts being directly associated 60 with an endless belt member 1 which is to be disposed at the front end of the complete machine and to be driven by any preferred means for accomplishing the desired results.

The belt 1 is here shown as formed of a 65 plurality of individual belts 2 whose edges contact with each other as clearly shown in Fig. 2. The entire belt structure 1 travels around a rectangular supporting frame 3 having a trio of guide sprockets 4 disposed 70 at its lower end and alined with three such sprockets 5 keyed to the horizontal shaft 6 at its upper end, the shaft 6 being mounted in appropriate bearings 7 carried by the laterally projecting ends of the upper end 75 bar 8 of the frame. As shown in the present case, the shaft 6 is driven by a sprocket wheel 9 secured to one of its ends, it being therefore evident that as said shaft is rotated in the proper direction, the upper 80 reaches of the belt members 2 passing over the sprockets 4 and 5, will be moved upwardly.

In addition to the sprockets 5, the end portions of the shaft 6 are shown as provided with additional sprockets 5^a which are spaced outwardly from said sprockets 5, and with still other sprockets 5^b spaced outwardly from the sprockets 5^a. The lower end of the frame, directly above the 90 sprocket wheels 4, is provided with alined bearings 10 in which a shaft 11^a is rotatably mounted, the opposite ends of this shaft being equipped with sprocket wheels 11 which aline with those 5^a and over which other 95 belts 2 pass, these belts being therefore necessarily of less length than those passing over the wheels 4 and 5.

Spaced above the bearings 10 and disposed at substantially the center of the 100 frame 3, is a pair of alined laterally extending bearings 12 in which an additional shaft 13^a carrying sprocket wheels 13 on its ends is rotatably mounted, said wheels being alined with the sprocket wheels 5^b and being 105 engaged by the lowermost loops of the outermost belt members 2, these members being of less length than those previously described, thus providing the belt member 1 with stepped edges at its lower end, this being advantageous since by its use, ditches of greater width at the top than at the bottom may be dug.

In the present case, the shaft 6 is shown

as provided with seven sprocket wheels, seven belt members 2 being therefore used in the complete machine, but it will be evident that if desired, certain of these belt members 5 may be removed or that by replacing certain of the shafts at the lower end of the excavator by longer shafts, the outermost belt members 2 could be lengthened, thereby allowing the belt member 1 to be 10 varied in design according to the use to which it is to be applied.

The belt members 2 hereinbefore described each comprise an endless chain 14 of the roller type passing over the upper 15 and lower guide sprockets, a plurality of overlapping rectangular plates 15 and 15^a, and excavating and elevating members 16 secured in contact with the outer sides of said plates 15^a, the latter as well as the 20 plates 15 being disposed against the outer side of the chain 14.

For the purpose of securing the plates 15 and the members 16 to the chain, similar devices 17 and 17^a are provided. The member 17 is in the form of a rectangular block or shank having a reduced neck upset at 18 in a rectangular opening in the plate 15, this shank having a pair of curved seats 19 in opposite sides which receive portions of certain rollers 20 of the chain 14, it being evident from the drawings (see more particularly Fig. 6), that the shank 17 is received by one of the links of said chain. The member 17^a is identical in construction with that 30 designated at 17 with the exception that its design is varied to a slight extent and it is passed through an elongated rectangular opening 18^a in the plate 15^a and is formed integrally with the excavating member 16.

Although the means just described is 40 preferably used for the purpose of securing the several overlapping rectangular plates to the chains 14, it will be evident that other means might easily be provided for this purpose without departing from the spirit of the invention. It is essential, however, that the plates either overlap each other or 45 abut so closely as to prevent earth from falling therethrough, and is likewise highly desirable to dispose the side edges of the adjacent rows of overlapping plates in such 50 close contact as to prevent the discharge of material through the spaces therebetween. It will thus be seen that the earth dug up by 55 the excavating and conveying member 16 will be supported not only thereon but upon the continuous flat faced belt member 1 and will be conveyed upwardly by these parts to the upper end of the excavating mechanism, 60 at which point it is delivered into a conveyer (not shown).

As seen most clearly in Fig. 2, the conveying members 16 are disposed in transverse V-shaped rows across the entire upper reach 65 of the belt member 1, and the transverse

cutting blades 21 of these members are of substantially the width of the belt member 2. This disposition of parts is highly essential since not only are V-shaped supports for the earth being elevated, provided, but the outermost of the rows of members 16 pass over the upper sprockets in advance of the lower member 16; thus tending to break up and loosen the body of earth, or the like supported by said members and assisting 70 greatly in allowing the same to deliver their contents upon the usual conveyer above mentioned. It may here be further explained, that the blades 21 of the members 16 are provided with no projections whatever at 80 the opposite ends of their front faces 21^a, thus also facilitating the discharge of earth from said members.

I am aware that heretofore conveying belts having V-shaped rows of buckets have 85 been provided but the results obtainable by the open sided members 16 cannot be obtained by the use of such buckets, since when ditching damp or muddy earth, the same packs within said buckets and cannot be discharged therefrom. By constructing the members 16 as shown in the drawings, however, no parts are provided in which the mud or earth can lodge, thus allowing the breaking action exerted upon the earth when 90 passing over the upper sprocket wheels, to effectively loosen and discharge such earth from the aforesaid members 16. Furthermore, this delivery of the elevated material is facilitated by the unique mounting of the 95 excavating members 16. In the present application, these members are shown as including the transversely disposed cutting blades 21 which are formed integrally with and project outwardly from the rear ends 100 of a plurality of necks 22 disposed longitudinally upon the belt members 2, it being to the front ends of these necks that the outer ends of the members 17^a are integrally joined. By connecting these front ends of 105 the necks 22 with the belts 2, it will be seen that as the latter pass around the uppermost sprocket wheels (see Fig. 1) the rear ends of the necks 22 and therefore the blades 21 will be thrown outwardly, thus dislodging 110 the material raised thereby. This outward swinging takes place rather suddenly and coacts with the breaking action exerted upon the material by the members 16, to effectively clear the entire upper end of the 115 excavator of earth even though same be damp and packed to a great extent.

When the machine is used for ditching earth in which numbers of roots are 120 encountered, or perhaps embedded brush, it becomes expedient in addition to the transverse blades 21; to provide longitudinal cutting blades 23 projecting forwardly from the intermediate portions of said blades 21. The blades 23 are here shown of substan- 125 130

tially triangular formation and as being secured by bolts 24 to longitudinal flanges 25 which project forwardly from the front faces 21^a of the members 16, the outer cutting edges 26 of the several blades 23 being preferably extended outwardly beyond the cutting edges of the blades 21. By this construction, it will be evident that as the members 16 are moved forwardly against the earth, the blades 26 will sever all roots and the like therein, thus allowing a more perfect operation of the machine and preventing the several excavating members from becoming clogged by the debris encountered.

15. The members 16 may be constructed in the manner previously described and the blades 23 may be secured thereto in the manner set forth or by practically any other preferred means. As illustrative of one embodiment of such additional means, Figs. 9 and 10 have been prepared. In these two figures, the blade 21' of the excavating member 16' is provided with a mortise 21" opening through its cutting edge, this mortise receiving a tenon 23" on the rear end of a longitudinally disposed cutting blade 23'. This blade 23' contacts with the longitudinally disposed flange 25' projecting forwardly from the blade 21' and outwardly 25 from the neck 22' of the excavating member, a single bolt 24' sufficing for securing the blade 23' against dislocation when this construction is provided.

Another manner in which the excavating and elevating members may be constructed is disclosed in Figs. 11 and 12 in which said members are designated broadly by the numeral 16', these members being of practically the same construction as those previously described with the exception that they are provided with no longitudinal cutting blades. They are equipped however, with attaching lugs 17" similar to those previously described.

45. In addition to the features just described, the members 16' are provided with attaching shanks 17' whereby they may be secured to the chains of the endless belt member as previously set forth, it being evident that in order to attach any of the excavating members or any of the plates 15, certain of the side plates of the chains 14 must be removed to allow for the insertion of the shanks 17, 17^a and 17' as the case may be.

55. It is a well known fact that when applying devices of the class previously described to use, the upper and lower reaches of the several endless belt members are apt to be warped inwardly by continued contact with the sides of the ditch. This would be an extremely undesirable mode of operation in a machine constructed in accordance with the present invention, since it would cause unnecessary friction to exist between the abutting edges of the several belt members. It

therefore becomes highly expedient to provide means for averting any trouble which might be caused by insufficient construction. It may here be explained, however, that when a ditch having stepped sides is being dug by the machine, the means to which I have reference is not as an essential part of the machine, as when the several belt members 2 are so disposed as to impart to the main belt member 1 but two angular lower 75 corners, thus forming the ditch with two upright parallel sides and a flat bottom. However, if in some cases it be found desirable, the construction in question may be used upon the belt member formed of the 80 central trio of belts 2, when said belts are positioned as shown in Fig. 2.

The essential construction just referred to is shown in Figs. 7 and 8 of the accompanying drawings, in which the belt members 2^a have been disposed as above set forth, for constructing a ditch with upright sides and a flat bottom. In these figures, a plurality of transverse rigid bars 50 is shown as secured at their ends by bolts or other appropriate fasteners to the outermost of the belt members 2, it being thus evident that regardless of the amount of contact existing between said members and the walls of the ditch, the former cannot be warped or injured in any manner whatsoever, since lateral thrust on each of the outermost belts 2^a is exerted directly upon the opposite belt.

In order to remove projections and loosen dirt from the side walls of the ditch, the opposite ends of the bars 50 are provided with smoothing shoes 51 preferably having their edges sharpened as seen at 52 whereby to remove any obstructions upon said walls. The shoes 51 could well be of any preferred construction, but they are shown in the present application and in practice, as preferably bent laterally from the ends of the bars 50, this being extremely simple yet very efficient construction.

From the foregoing description, taken in connection with the accompanying drawings, it will be evident that a highly efficient excavating machine has been provided for producing the desired end, yet that the same will be comparatively simple in construction.

In the accompanying drawings, certain specific details of construction are illustrated for producing probably the best results and in the foregoing description, such details have been specifically described. It will be evident, however, that I need not be limited thereto, otherwise than to the extent to which the appended claims limit me.

I claim:

1. In combination, a belt member comprising a plurality of individual belt members movable in the same direction and having their edges disposed in contact with

each other, and a plurality of excavating members carried by said belt members.

2. In combination, a plurality of individual belt members of different lengths movable in the same direction and having their edges disposed in contact with each other, and a plurality of excavating members carried by said belt members.

3. In combination, an endless belt member having thereon a plurality of excavating and elevating members each having a transverse permanent blade, a longitudinal attaching flange extending forwardly therefrom, and a removable longitudinally disposed blade leading forwardly from the transverse blade and detachably secured to said flange.

4. In combination, an endless belt member having thereon a plurality of excavating and elevating members each having a transverse permanent blade having a mortise, a longitudinally disposed removable blade having a tenon received by said mortise, and releasable means preventing relative movement of the two blades.

5. In combination, an endless belt member having thereon a plurality of excavating and elevating members each having a permanent transverse blade having a mortise and a rigid flange continuing forwardly from said blade, a longitudinally disposed blade having a tenon received by the mortise, said longitudinal blade being disposed in contact with the flange, and a releasable fastener passing through said longitudinal blade and said flange.

6. In combination, a plurality of endless chains disposed side by side and each having a plurality of plates on its outer side, the edges of the plates of one chain being disposed contiguous to those on the adjacent chain, and excavating and elevating members disposed contiguous to the outer faces of said plates and movable therewith.

7. In combination, a plurality of endless chains disposed side by side and each having a plurality of overlapped plates on its outer side, the side edges of the plates on one chain being disposed contiguous to those on the adjacent chain, and excavating and elevating members disposed contiguous to the outer sides of said plates and movable therewith.

8. In combination, a roller chain, plates contacting with one side thereof, and plate attaching shanks snugly disposed between

certain of the rollers of the chain and having curved seats receiving the same.

9. In combination, a sprocket chain, plates disposed in contact with one side thereof and having openings, and excavating members having attaching shanks extending through said openings and anchored in respect to the chain.

10. In combination, a sprocket chain, plates disposed in contact with one side thereof and having openings, and excavating members having attaching shanks extending through said openings, received by certain links of the chain, and having seats in turn receiving portions of said links.

11. In combination, a sprocket chain, plates disposed in contact with one side thereof, attaching shanks projecting beyond the plates and received by certain links of the chain, and seats on the shanks in turn receiving portions of said links.

12. An excavating device for attachment to endless belt members and comprising a blade having a mortise between its ends for the reception of a tenon on an additional blade.

13. An excavating device for attachment to an endless belt member and comprising a blade having a mortise between its ends, and a flange extending laterally from one of its sides adjacent said mortise, the flange being adapted for the attachment of an additional blade, and the mortise being designed to receive therein a tenon on the additional blade.

14. In combination, a main endless belt member composed of a plurality of individual belt members movable in the same direction and having their edges disposed in contact, a plurality of excavating buckets carried by the individual belt members, and a plurality of bars extending transversely from one edge of the main belt member to the other edge thereof and having their opposite ends bent laterally to form shoes for contact with the sides of the ditch to prevent binding of the individual belt members against each other, the portion of the bar between the two shoes being free from projections.

In testimony whereof I have hereunto set my hand in presence of two subscribing witnesses.

MICAJAH L. POULTER.
